[57] CLAIM

The ornamental design for a shoe shine stand, substantially as shown and described.

DESCRIPTION

FIG. 1 is a front elevational view of a shoe shine stand showing my design.

FIG. 2 is a rear view of the shoe shine stand of FIG. 1. FIG. 3 is a right side view, taken along line 3—3 of FIG. 1, the left side view being a mirror image thereof. FIG. 4 is a top view, taken along line 4—4 of FIG. 1. FIG. 5 is a bottom view, taken along line 5—5 of FIG. 1.
